DISPLAY CARD CARRIER

Robert E. Merritt and Warren C. Nichols, Mount Airy, N.C., assignors to Renfro-Hosiery Mills Company, Mount Airy, N.C., a corporation of North Carolina
Filed Apr. 1, 1966, Ser. No. 539,479
7 Claims. (Cl. 40—102)

ABSTRACT OF THE DISCLOSURE

A display card carrier including two coextensive spaced, U-shaped guideways with a handle conveniently located between the guideways for supporting a plurality of display cards in a balanced condition during transportation. The position of the handle between the guideways also permits the carrier to be lifted by one hand when the cards are in a displayed condition.

This invention relates to portable carriers and more specifically to a portable carrier for supporting and displaying a plurality of cards thereon.

In business sales operations, since products of a line are often shown and sold by traveling sales representatives, it is highly desirable for such representatives to be able to present to the customer in a quick, easy manner, an attractive display of the product line. Quite often, products are bulky and difficult to carry and, as a consequence, consume excess space when packaged in conventional carrying devices such as suitcases, briefcases, boxes, and the like. Additionally, when products must be packaged for transportation in this way, a delay is encountered when arranging the products in a suitable manner for display to a customer.

It is therefore an object of the present invention to provide a novel portable carrier for supporting products and forming therewith a display case for quickly showing the products to a customer in an attractive, arranged manner which case is easy to hand carry when traveling from customer to customer.

It is a more specific object of the invention to provide a novel portable card display case composed of a carrier having a pair of substantially coextensive, spaced, U-shaped guideways supporting a plurality of display cards thereon and interconnected by means having a handle located thereon in such a way that the cards are easily transported and may be manipulated on the guideways to display their contents without removing them from the carrier.

Some of the objects of the invention have been stated, other objects will appear as the description proceeds when taken in connection with the accompanying drawings, in which:

FIGURE 1 is a perspective view of a portable card display case incorporating the novel features of the present invention shown in the normal closed position for carrying;

FIGURE 2 is a side elevation of the display case shown in FIGURE 1;

FIGURE 3 is a perspective view of the display case of FIGURE 1 shown in an open, display position; and

FIGURE 4 is a side elevation of the carrier portion of the display case of FIGURE 1 shown with the cards removed.

Referring now to FIGURE 1, a portable card display case comprising a carrier 11 is shown having a plurality of display cards 12 attached thereto. The carrier is composed of a pair of spaced, substantially coextensive, elongated U-shaped guideways 13, 14 which have opposed runs 13a, 13b and 14a, 14b, respectively. Guideways 13

2

and 14 are rigidly attached to each other by connecting means composed of a pair of suitably bent rods 15, 15a which are attached to and extend from the ends of runs 14a and 13a, respectively, and a handle 16 interconnecting the rods. As seen in FIGURE 3, rods 15 and 15a are bent adjacent the ends of runs 13a and 14a to form L-shaped footrests 17 and 18, which will be discussed hereinafter. The rods have substantially parallel straight portions 19, 19a which extend from the footrests toward the closed ends of the guideways and position handle 16, attached thereto, approximately midway of the length of the guideway runs.

The L-shaped footrests have corresponding reaches 17a and 18a which are attached to and extend inwardly from the ends of runs 13a and 14a, respectively, and reaches 17b and 18b which are attached to reaches 17a and 18a and extend at right angles thereto in the general direction of runs 13b, 14b. Retaining means, shown as a pair of threaded knobs 20, 20a engage threaded ends of runs 14b and 13b, respectively, to removably secure the cards on the guideways. As best seen in FIGURE 4, the knobs lie in a common plane with footrests 17 and 18 and cooperate therewith to support the carrier in an erect position with the guideway runs substantially vertical when the display case is open, as seen in FIGURE 3. Footrest portions 17 and 18 also act as card stop means to prevent movement of the cards past the ends of guideway runs 13a and 14a.

In FIGURES 1 and 2, the card display case is shown in a closed condition with the carrier in a horizontal position and all of the cards 12 spaced closely along and supported by lower runs 13b, 14b of the guideways. Cards 12 are provided with guideway receiving means or eyelets 21 located adjacent an edge of each card. The cards are maintained in this position with the display case closed by suitable fastening means shown as a strap 22 suitably secured to outermost or distal of cards 12 by snaps 23. The length of the strap preferably corresponds to the distance between snaps on distal cards when the cards are in contiguous, side by side relation as shown. The handle 16 is preferably located, as shown, substantially midway along the length of the guideway runs. By positioning the handle 16 at this location, which approximately coincides with the center of gravity of the display case, the case is more stable and can be more readily carried without off-balance of the cards.

FIGURE 3 shows the portable card display case of the present invention in an open condition whereby the cards and their contents can be displayed. For display, the case is normally placed on a flat surface with the ends of the guideways lowermost in contact with the surface. In this position, footrests 17 and 18 cooperate with knobs 20, 20a on the ends of runs 14b and 13b to maintain the carrier erect and the runs in a substantially vertical position. As can be seen, by releasing strap 22 from one of the distal cards, the respective faces of the cards can be viewed by slidably moving the cards, in sequence, along the runs of guideways 13, 14. For purposes of illustration, samples S of a hosiery product line are shown in broken lines attached to the opposite faces of the cards 12 and FIGURE 3 illustrates the ease with which the hosiery may be displayed.

It is to be noted that the location of handle 16 on the carrier enables the display case to be easily moved from position to position when the case is open. As seen in FIGURE 3, handle 16 readily can be gripped and the case entirely supported by hand while displaying the cards therein. Additionally, location of handle 16 between guideway 13 and 14 and in a plane passing between the opposed runs of each guideway allows the cards to be slidably manipulated on the carrier for display without interference with the handle.

In the drawings and specification there has been set forth a preferred embodiment of the invention and, although specific terms are employed, they are used in a generic and descriptive sense only and not for purposes of limitation, the scope of the invention being defined in the claims.

What is claimed is:

1. A carrier adapted for supporting and displaying a plurality of cards, said carrier comprising a pair of spaced, substantially coextensive U-shaped guideways for slidably supporting cards thereon and having corresponding pairs of ends, each of said guideways comprising opposed runs, means associated with one pair of ends of said guideways for removably retaining cards on said guideways, a handle located between said guideways and between said opposed runs thereof, and means connecting said handle to said guideways.

2. A carrier according to claim 1 wherein said handle is located substantially midway of the length of the runs of said guideways to thus position the handle substantially centrally of the carrier to facilitate transportation of said carrier.

3. A portable card display case comprising, in combination, a card carrier and a plurality of cards supported thereby, said carrier comprising a pair of spaced, substantially coextensive U-shaped guideways having corresponding pairs of ends, said cards being positioned on said guideways for slidable movement therealong, each of said guideways comprising opposed runs, means associated with one pair of ends of said guideways removably retaining said cards on said guideways, a handle, and means connecting said handle to said guideways, said handle and said connecting means being located between said guideways and between said opposed runs thereof and so posi-

tioned relative to said opposed runs thereof to permit said cards to be freely movable throughout the extent of said guideways.

4. A display case according to claim 3 wherein said handle is located substantially midway of the length of the runs of said guideways to thus position the handle substantially centrally of the carrier to facilitate transportation of said display case.

5. A display case as defined in claim 3 including fastening means associated with said cards for maintaining said display case closed with said cards in close association to each other.

6. A display case as defined in claim 5 in which said fastening means includes a strap attached to distal cards of said plurality of cards.

7. A display case as defined in claim 3 wherein said connecting means includes footrests for supporting the carrier in an erect position in which said opposed runs of the guideways are substantially vertical with said ends of the guideways lowermost, and wherein said means removably retaining said cards terminates in a common plane with said footrests to aid in maintaining said carrier in said erect position.
